UNITED STATES PATENT OFFICE.

CARL H. ROBINSON, OF SNOW HILL, ALABAMA.

COTTON-SQUARE DESTROYER.

1,180,434.

Specification of Letters Patent. Patented Apr. 25, 1916.

Application filed June 10, 1914. Serial No. 844,284.

To all whom it may concern:

Be it known that I, CARL H. ROBINSON, a citizen of the United States, residing at Snow Hill, in the county of Wilcox, State 5 of Alabama, have invented certain new and useful Improvements in Cotton-Square Destroyers; and I do hereby declare the following to be a full, clear, and exact description of the invention, such as will enable 10 others skilled in the art to which it appertains to make and use the same.

This invention relates to a cotton square destroyer.

An object of the invention is to provide a 15 device which will readily blow the squares from beneath the rows of plants in a cotton field.

A further object of the invention is to provide a device that will at the same time 20 destroy the said cotton squares so that any boll weevils which may be in the squares will at the same time be destroyed.

With these and other objects in view, this 25 invention resides in the novel features of construction, formation, combination and arrangement of parts as herein set forth and subsequently claimed.

Referring to the drawing: Figure 1 is a 30 side elevation of my device. Fig. 2 is a rear elevation. Fig. 3 is a front elevation thereof. Fig. 4 is a sectional view of the blower. Fig. 5 is a plan view of the device. Fig. 6 is a detail of the gasolene tank.

Referring to the drawing by reference 35 characters wherein like parts are indicated by like characters throughout the several views: my device comprises a wooden beam 1 which is supported on a wheel 2, which wheel is connected to the said beam by brackets 3. A pair of handles 4 are bolted, as at 5, to the rear end of the beam so that the device may be operated. On the shaft 6 of the wheel 2 is fixedly mounted a gear wheel 7, the purpose of which will appear 40 later. A blower 8 is mounted on the beam 1 and comprises a fan 9, a casing 10 and a tube 11, which tube is swiveled on a neck 12 of the casing 10 so that it may be moved relative to said casing. A gear casing 13 45 is secured to the side of the casing 10 and has a pair of gears 14 rotatably mounted therein, one of said gears being mounted on the shaft 15 of the fan 9 and the other of said gears meshing with the aforementioned 50 gear and mounted on a shaft 16. On this

shaft and on the outside of the casing 13 is an additional gear 17 over which a chain 18 passes, which chain also passes over the gear 7.

When the vehicle is advanced the rotation 60 of the wheel 2 through the operating mechanism described causes the fan 9 to be rotated and thus air is forcibly ejected from the tube 11. In operation this tube extends downwardly from the beam 1 in an inclined 65 direction, as shown in Fig. 3 in full lines and is supported by a chain 19 suspended from a rod 20, which rod is secured to the upper face of the beam between the edges thereof so that a portion of the said rod 70 bears against the edge of the beam and is thus supported in a horizontal position. By virtue of the connection between the tube 11 and the neck 12 the said tube may be swung 75 to either one side or to the other of the said beam when the device is in operation, or it may be swung into a vertical position when the device is inoperative.

Pivotedly supported in bearings 21 on the 80 handles 4 is a gasolene tank 22 which has a pressure pump 23 secured thereto and connected thereto by a pipe 24, in which pipe 85 is a needle valve 25. A pipe 26 is secured to the said tank and has a valve 27 therein, and this pipe 26 extends downwardly and has connected thereto at its lower end a horizontal pipe 28 on which is mounted a plurality of burners 29 of the type adapted to burn gasolene. The said burners have a plurality 90 of holes 30 therein through which the flame caused by the burning of the gasolene is forcibly ejected by the pressure created in the tank 27 by the pump 23.

In operation the tube 11 is supported in 95 its downwardly inclined position and the device is pushed between two rows of plants so that the end of the tube 11 will be adjacent the lower portions of one of the rows. During the advance of the vehicle by virtue 100 of the connection between the fan 9 and the drive wheel 2 air is forcibly ejected from the tube 11 and blows all of the squares and other matter which have collected beneath the plants in the row which is being operated upon to positions on the other side of said row and in the ditch between that row and the next adjacent row. Before the vehicle is pushed up the ditch in which the squares and other matter have been blown 105 the gasolene burners 29 are lighted and the 110

tube 11 swung to the opposite side of the beam 1 so as to blow the squares from beneath the row of plants which have not already been operated upon. During the 5 advance of the vehicle to perform this operation the flames which escape from the holes 30 in the burners 29 burn the squares which have been previously blown into the ditch in which the vehicle is being pushed 10 and during this burning operation boll weevils which are in the said squares are destroyed.

From the foregoing description, it may be seen that I have provided a device which 15 will effectually blow the squares which have become infested with boll weevils or other insects from beneath the rows of plants and will at the same time burn the squares and insects which have been previously blown 20 from beneath the plants, and I have further provided a device which will accomplish the above results without in any way coming in contact with the plants or causing the plants to be subjected to heat.

25 I do not wish to be limited to the particular construction of my invention shown, for it is obvious that numerous changes may

be made within the scope of the invention as defined by the claim.

What is claimed is:—

In a cotton square destroyer, the combination with a beam and a wheel for supporting the same, of a blower mounted on said beam, an angular tube swivelly connected to said blower in such manner that it may be swung to extend downwardly and outwardly from either side of the beam, means for supporting the tube in said positions, consisting of a rod extending transversely of the beam and a flexible member secured to the tube and adapted to be secured to either end of the rod, and a chain operatively connected to the wheel and to the fan in said blower to rotate the fan upon the advance of the wheel to cause a current 45 of air to pass outwardly through the said tube.

In testimony whereof, I affix my signature, in the presence of two witnesses.

CARL H. ROBINSON.
